Inventor,

Edmund B. Carns,
By his Attorney,
Ramsay Hoguet.

UNITED STATES PATENT OFFICE.

EDMUND BURKE CARNES, OF NEW YORK, N. Y.

METAL STRUT.

Application filed March 5, 1927, Serial No. 173,067. Renewed January 14, 1929.

My invention relates to improvements in metal struts and the object of my invention is to produce a metal strut having a maximum of strength and a minimum of weight.

5 The invention is intended primarily for use in aeroplanes, although it can be used for other purposes, but it is especially designed for use in fuselage and wing structures of aeroplanes to brace various parts 10 and to this end it is desirable to have a strut which is very strong in proportion to its weight. The invention, therefore, is to be a structure that can be built commercially to a figured stress requirement and lose none 15 of its structural value when joined to other members.

My invention also embraces the method of making a strut of a kind hereinafter described. My invention is also intended to 20 produce a strut which can be conveniently and commercially made from metal T's and comprises the shaping and uniting of these T's to form a strut having the desired characteristics. This will be better understood 25 from the description which follows:

Reference is to be had to the accompanying drawings forming a part of this specification, in which similar reference characters indicate corresponding parts in all the 30 views.

Fig. 1 is a perspective view of a conventional T used in the manufacture of my improved strut.

Fig. 2 is a perspective view showing the T 35 as shaped for use and for combining with another similar T.

Fig. 3 is a side elevation of the complete strut.

Fig. 4 is a broken end perspective showing 40 how the strut can be made to have a mortise end.

Fig. 5 is an end perspective showing how the strut can be made with a tenon end, and

Fig. 6 is a broken end perspective showing 45 another form of the strut end.

In carrying out my invention I employ metal T's of conventional shape comprising, as shown in Fig. 1, the flange 10 and web 11. This T is bent or curved so that the flange 50 10 will be bent and crowning as shown at Fig. 2 and the web 11 when the T is bent will be bent down to the line 12 in Fig. 2. The web is afterwards cut off straight as shown at 13, thus making the web 11 of a 55 reduced height at the end portions of the T and, if desired, the extreme end portions of

the web 11 can be cut away as shown at 14, so that a mortise will be formed in the complete structure, as hereinafter described. The extreme end portions 15 of the flange 10 60 are left of the normal width of the flange and are unbent so that when two T's are brought together, as presently described, the end parts 15 will be generally parallel, as shown in Fig. 3. These end portions can be 65 perforated if desired as shown at 18 to facilitate bolt attachments, and the web 11 is also perforated at the necessary points as shown at 17. When two T's have been thus formed, they are placed together with the 70 webs overlapping and rivets 17' or equivalent fastenings inserted in the registering holes 17 of the two webs 11, and thus when the two parts of the strut, that is, the two T's, are united in this way a strong structure is formed, which will be thickest in the 75 middle and will taper towards the ends. It will be noted that the web of one T member will bear against the flange of the other member thus strengthening the same and taking the shearing strain off the fastening elements 17'. Before the parts are united, as above stated, the flanges 10 can be reduced between their middle and end portions, as shown at 16, and as the 80 flanges and webs are both reduced, it will be seen that the structure as a whole can be figured so that the metal will be disposed in a way to produce the greatest strength in 85 proportion to the weight and no surplus metal need be used.

In the formation of the T in the manner described, if the parts 14 are cut away, as indicated in Figs. 1 and 2, mortises 19 will be left between the end portions 15 of the 90 two T flanges, which in some cases is desirable, but on the other hand if a tenon is to be formed on either or both ends of the strut the flanges can be cut away at the end parts, as shown in Fig. 5, leaving a protruding tenon 20. If desired, the web members 11 and the flange member 15 may be left the full length of the strut, as shown in Fig. 6, so that the strut will have a solid end portion representing neither a mortise nor tenon 100 effect.

Thus, it will be seen that by the use of conventional metal T's which can be of any preferred light strong metal, the strut as a 105 whole can be economically made, will have unusual strength, and if the parts are properly figured the maximum strength can be

located at desired points so as to make the strut, as a whole, a commercial economical structure. I have shown a design of strut which is capable of use in many parts of aeroplane construction, a use to which the strut is especially designed, but obviously the structure is not limited to any particular use.

I claim:

- 10 1. An improved strut element comprising a metal T bent to a curve with its web straight on its outer edge, with its flange reduced in width between the middle and end portions and with the end portions of the flange projecting beyond the ends of the web.
- 15 2. An improved strut element comprising a metal T bent to a curve with its web straight on its outer edge, with its flange gradually reduced from the middle towards the end parts, and with the end portions of the flange perforated and projecting beyond the end portions of the web.
- 20 3. An improved strut comprising two oppositely curved metal T's with separate webs reduced in height towards the ends disposed to lie one against the other with the outer edge of one web bearing for at least a part of its length against the flange of the opposed member, said webs being fastened together and the flanges being gradually reduced from the middle towards the ends of the strut.
- 25 4. An improved metal strut comprising

two oppositely curved metal T's with separate webs reduced in height towards the ends disposed to lie one against the other with the outer edge of one web bearing for at least a part of its length against the flange of the opposed member, said webs being fastened together and the flanges being gradually reduced from the middle portion towards the ends, with the end parts of the flanges projecting beyond the end portions of the webs.

5. An improved strut according to claim 4, further characterized by having the protruding ends of the flanges relatively wide and parallel with each other.

6. An improved strut element comprising a metal T bent to a curve in the plane of its web, said T having the outer edge of its web substantially straight and with its flange reduced from the middle towards the end parts.

7. An improved strut comprising two metal T's with the web of each bearing in part against the flange of the other, said webs being fastened together, said T's having flanges curved in the plane of said webs and said webs being reduced in height towards the ends.

In testimony whereof, I have signed my name to this specification this 4th day of March, 1927.

EDMUND BURKE CARNES.
